UNITED STATES PATENT OFFICE.

EBEN H. CARRUTHERS, OF ASTORIA, OREGON.

SUPPORT.

Application filed July 11, 1923. Serial No. 650,930.

To all whom it may concern:

Be it known that I, EBEN H. CARRUTHERS, a citizen of the United States, residing at Astoria, in the county of Clatsop and State 5 of Oregon, have invented certain new and useful Improvements in Supports, of which the following is a specification.

This invention relates to supports, and more particularly to holders for tooth paste 10 tubes and the like.

An object of the invention is the provision of a support to retain a tooth paste tube in an inverted position whereby the brush may be placed under the tube and the paste dis- 15 charged from the tube onto the brush.

A further object is the provision of a closure member normally retained over the outlet opening of the tube and adapted to be readily moved to an open position when the 20 brush is inserted.

A further object is the provision of a clamp consisting of a pair of adjustable arms whereby the tubes of different sizes may be inserted in the holder.

In the accompanying drawings, I have shown one embodiment of the invention. In this showing:

Figure 1 is a perspective view showing the tube in position,

Figure 2 is a central vertical sectional view,

Figure 3 is a top plan view with the tube removed,

Figure 4 is a transverse sectional view on line 4-4 of Figure 3, and

Figure 5 is a detail perspective view of the closure arm.

Referring to the drawings, the reference numeral 1 designates a suitable base or support provided with openings 2. Suitable fastening elements 3, such as screws, or the like, are adapted to be arranged in the openings 2 to secure the base to a vertical support, such as a wall. The clamping bracket 40 consists of a substantially U-shaped member having a base 4 secured to the base 1 by a suitable fastening element 5 and a pair of substantially parallel arms 6. The outer ends of these arms are arranged in a horizontal plane, as at 7, and are provided with substantially semi-cylindrical recesses 8. These arms are resilient and are adapted to be adjusted toward each other by means of a set screw 9. A collapsible tube 10 is arranged in an inverted position over the support and the neck of the tube is adapted to

be received in the cut out portions 8 of the arms 6. The screw 9 is then tightened to securely clamp the tube in position. A closure arm 11 is pivotally mounted beneath 60 the bracket. As shown, the rear end of this arm is provided with an upwardly extending portion 12 having a sleeve 13 formed on its end and adapted to receive a pivot pin 14 carried by the clamping arms. This upwardly extending portion of the closure arm is provided with an opening 15 for the passage of a pin 16. The end of the pin passes through the base and is bent over, as at 17. A coil spring 18 surrounds the pin. 70

The forward end of the closure arm is provided with a downwardly curved portion 19 and adjacent this downwardly curved portion there is provided a cap 20 adapted to fit over the discharge opening of the tube and having a cork plate 21 arranged therein. A hook 22 may be formed on the base to receive a tooth brush.

In operation, the brush is placed on the downwardly curved portion 19 of the supporting arm and moved rearwardly with a slight pressure to move the closure arm downwardly and permit the brush to assume a position beneath the discharge opening of the tube. This downward movement of the arm moves the upwardly extending portion 12 toward the base and places the spring 18 under tension. When the brush is in proper position, the tube is squeezed to discharge the desired amount of tooth paste. As soon as the brush is removed, the spring returns 90 the closure arm to normal position. By means of the device shown, tooth paste and other similar semi-solid substances may be readily dispensed from collapsible tubes 95 without handling the tube and accidentally discharging any of its contents. The device is further advantageous for the reason that the tube may always be found in its proper place and is automatically closed when the 100 brush is removed.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I 110 claim:

1. A holder for tooth paste tubes comprising

ing a base, a pair of clamping arms mounted on said base, said arms being provided with substantially semicircular cutout portions adapted to engage opposite sides of the neck 5 of an inverted tube, means for clamping said arms together, a closure arm pivotally mounted beneath said clamping arms, a spring to normally retain said closure arm in raised position, and a cap carried by said 10 closure arm and adapted to fit over the outlet opening of said tube.

2. A holder for tooth paste tubes comprising a vertical base, a horizontal supporting member secured at its inner end to said base, 15 said supporting member including a pair of spaced arms having horizontal portions at their outer ends provided with substantially semicircular cutout portions adapted to re-

ceive the neck of an inverted tube, a closure arm arranged below said supporting member, the inner end of said closure arm being turned upwardly and arranged between the arms of said supporting member, a pivot pin connected between the arms of said supporting member and pivotally supporting the 25 upturned end of said closure arm, a pin carried by said base and passing through an aperture in the upturned end of said closure arm, a coil spring surrounding said last named pin and normally urging said closure arm to raised position, and a cap carried by 30 said closure arm and adapted to cover the outlet opening of the tube when said closure arm is in normal position.

In testimony whereof, I affix my signature.
EBEN H. CARRUTHERS.
